UNITED STATES PATENT OFFICE.

EMERY G. GILSON, OF SCHENECTADY, NEW YORK, ASSIGNOR TO GENERAL ELECTRIC COMPANY, A CORPORATION OF NEW YORK.

CARBURETOR.

1,407,024.

Specification of Letters Patent. Patented Feb. 21, 1922.

Application filed August 26, 1919. Serial No. 319,980.

To all whom it may concern:

Be it known that I, EMERY G. GILSON, a citizen of the United States, residing at Schenectady, in the county of Schenectady, 5 State of New York, have invented certain new and useful Improvements in Carburetors, of which the following is a specification.

The present invention relates to carburetors such as are used in connection with internal combustion engines for supplying a mixture of fuel and air thereto and has for its object to provide a carburetor of improved structure and arrangement.

15 For a consideration of what I believe to be novel and my invention, attention is directed to the accompanying specification and the claims appended thereto.

In the drawing, Fig. 1 is a sectional view 20 of a carburetor embodying my invention; Fig. 2 is a sectional view of certain parts on a scale larger than Fig. 1, and Fig. 3 is a view similar to Fig. 2 of a modification.

Referring to the drawing, 5 indicates a 25 fuel chamber of a carburetor and 6 an annular float therein which is connected by a lever 7 to a valve 8 for controlling the admission of fuel through fuel inlet 9 to chamber 5. Fuel may be fed to inlet 9 from any 30 suitable source of supply. Float 6 serves to maintain a constant level of fuel in chamber 5 in the well understood manner and may be adjusted to maintain the desired level by adjusting the valve 8.

35 The upper wall of fuel chamber 5 is curved downwardly so it projects into the center of float 6 and at its lowermost part terminates in a wall 12. The lower surface of wall 12 is flat and depending therefrom 40 is a shield ring 13. The upper surface of wall 12 is curved as shown and is provided at its central portion with a cone-shaped projection 15. 16 indicates the upper wall 45 of the carburetor and projecting through an opening in it is a mixing tube 17, the outer end of which is adapted to be connected to the intake manifold of an engine as is well understood. The inner or lower end of mixing tube 17 terminates adjacent to 50 wall 12 at the base of cone-shaped projection 15 and on its end is a ring 19, which may or may not be an integral part of tube 17, the outer surface of which defines with 55 curved wall 11, an annular venturi shaped air passage 20. Surrounding mixing tube

17 is an air chamber 21 to which air is admitted through an air inlet 22.

Fuel is admitted from fuel chamber 5 to mixing tube 17 through a plurality of small orifices 23 located in wall 12 at the base of cone-shaped projection 15, the portion of wall which defines the orifice being very thin. This locates orifices 23 at the throat of the venturi-shaped air passage 20. Two or more orifices 23 may be utilized spaced 65 around the base of projection 15 and they may be provided by forming orifices in very thin portions of wall 12 as indicated at 23^a in Fig. 3 or by providing holes 24 in wall 12 over which are fastened thin plates 25 70 which contain orifices 23. By providing such orifices 23 or 23^a through which fuel is fed the proportion of fuel to air made by the carburetor will be substantially uniform 75 irrespective of the rate of flow of the air and the viscosity of the liquid fuel, that is to say, the mixture will be uniform at all loads on the engine.

Depending from the lower central portion of plate 12 is a rod 26 which projects 80 through the bottom wall of fuel chamber 5 and is fastened therein by washers 27 and a nut 28. Through the longitudinal center of rod 26 is a passage 29 which at its upper end communicates with a small passage 30 85 through cone-shaped projection 15. The purpose of this is to provide an overflow or drain for fuel in case the carburetor becomes flooded. The outer end of passage 29 may open to atmosphere or may be connected 90 with some suitable receptacle.

Mixing tube 17 is preferably divided longitudinally into two parts or passages by a partition 31 and in each of said passages is arranged a valve 32 for controlling the flow 95 of mixture from the mixing tube to the engine. Valves 32 are pivoted therein at the edge remote from partition 31. By this means as the valves are opened the mixture passes along close to the surface of partition 31. Any suitable means such as the rods 32^a may be provided for operating valves 32 in the desired sequence. By providing two separate passages in the mixing tube it will be seen that in operation first 100 one passage may be opened and then, as the load becomes greater, the other. This gives in substance the advantage of a smaller carburetor for starting and for use at light loads and a larger carburetor for heavy 105 110

loads and results in substantial economy in the use of fuel.

I also preferably arrange the carburetor so that the throat of the annular venturi shaped passage 20 may be adjusted and to this end I arrange the mixing tube and the wall 12 so they may be moved toward and away from each other. As one manner of doing this, I may make the mixing tube 17 in two parts as shown, one of which telescopes within the other as indicated at 33, and provide a suitable adjusting means as a rack 34 and pinion 35 whereby the lower end of the mixing tube may be moved away from and toward wall 12. The pinion 35 may be arranged to be turned in any suitable manner; in the case of an automobile I preferably arrange a suitable member located within reach of the driver so that he may adjust the same while the car is running. In starting the end of the mixing tube will be moved closer to wall 12 so as to reduce the area of the venturi throat which will give an increased suction effect. After the engine is started the end of the mixing tube may be moved slightly farther away from wall 12 thereby increasing the area of the throat of the venturi passage with the result that the suction will be less and the mixture thinner.

In operation, the float 6 and valve 8 are adjusted so that when the engine is idle a fuel level will be established which is slightly above the orifices 23. When the engine is operating air is drawn in through air inlet 22 to annular chamber 21 from which it passes in an annular sheet down through venturi shaped passage 20, hence at a right angle across the orifices 23 and then upward into mixing tube 17. When starting the engine, as fuel is present above orifices 23 such fuel will be taken up very readily by the air, carried along into the mixing tube, and mixed with the air. This assures a sufficiently rich mixture to make starting easy. After the engine is started and the carburetor has been used a short time, the fuel above orifices 23 will have been used up. The passage of the air across orifices 23 will then draw fuel up through them for mixing with the air and due to the arrangement of the orifices a very uniform mixture of the desired richness may be maintained at all speeds. The arrangement therefore gives automatically a rich mixture for starting and a leaner mixture for running. At any time the richness of the mixture may be adjusted by moving the inner end of mixing tube 17 toward or away

from wall 12. The fact that air enters the 60 mixing tube as an annular sheet coming in from all sides and flowing at a right angle across orifices 23 results in the fuel being initially well distributed through the air.

In accordance with the provisions of the 65 patent statutes, I have described the principle of operation of my invention, together with the apparatus which I now consider the best embodiment thereof, but I desire to have it understood that the apparatus shown 70 is only illustrative and that the invention may be carried out by other means such as come within the scope of the appended claims.

What I claim as new and desire to secure 75 by Letters Patent is:—

1. In a carburetor, a fuel chamber having a top wall which curves inwardly to form a recess, a mixing tube which depends into said recess and forms with the surface of the top wall an annular venturi-shaped air passage, a plurality of thin portions in the wall at the bottom of said recess said portions being provided with orifices through which fuel is fed from the fuel chamber to 80 the mixing tube, said orifices being spaced around the lower end of the mixing tube and located at the throat of the venturi-shaped passage, and means for maintaining a substantially constant level of fuel in the fuel 85 chamber slightly above the plane of said orifices whereby a small supply of fuel will be provided at the throat of the venturi-shaped passage above the orifices for starting.

2. In a carburetor, a fuel chamber having a top wall which curves inwardly to form a recess, a mixing tube which depends into said recess and forms with the surface of the top wall an annular venturi-shaped air passage, means forming orifices in the wall at the bottom of said recess through which fuel is fed from the fuel chamber to the mixing tube, said means comprising thin plates having openings therein, said orifices being 100 spaced around the lower end of the mixing tube and located at the throat of the venturi-shaped passage, and means for maintaining a substantial constant level of fuel in the fuel chamber slightly above the 105 plane of said orifices whereby a small supply of fuel will be provided at the throat of the venturi-shaped passage above the orifices for starting.

In witness whereof, I have hereunto set 115 my hand this 25th day of August, 1919.

EMERY G. GILSON.
